UNITED STATES PATENT OFFICE.

NORWOOD H. KNOWLTON, OF ROCKPORT, MASSACHUSETTS, ASSIGNOR TO UNITED SHOE MACHINERY CORPORATION, OF PATERSON, NEW JERSEY, A CORPORATION OF NEW JERSEY.

MACHINE FOR TREATING SHOE UPPERS.

Application filed March 17, 1922. Serial No. 544,581.

To all whom it may concern:

Be it known that I, NORWOOD H. KNOWLTON, a citizen of the United States, residing at Rockport, in the county of Essex and 5 State of Massachusetts, have invented certain Improvements in Machines for Treating Shoe Uppers, of which the following description, in connection with the accompanying drawings, is a specification, like reference characters on the drawings indicating like parts in the several figures.

This invention relates to upper treating machines. The invention is herein illustrated as embodied in a machine especially designed 15 for forming and assembling the uppers of stitchdown boots and shoes upon their lasts preparatory to lasting.

Heretofore the assembling of stitchdown shoes has been performed by hand, the upper, including usually a counter previously 20 molded with an outturned flange, being placed over a last to the bottom of which a sole has been attached with its margin projecting beyond the periphery of the last. 25 The upper is then drawn against the rear end of the last, located, and secured by a tack at the rear end of the last. In this operation the workman sees that the upper is in proper position peripherally of the 30 last, for example by locating the back seam at the center of the rear end of the last, and that the upper is positioned vertically so that there will be enough material of the upper and counter to be worked into the angle between the projecting sole margin and the 35 side of the last, no attempt being made, however, to work the upper into said angle, this being left for the subsequent lasting operation which is usually performed by the 40 stitchdown staple laster.

In view of these conditions, an object of this invention is to provide a machine to facilitate the lasting operation by locating the upper on the last, forming the margin of 45 the upper into the angle in which it is to lie when lasted, and securing the upper to its last preparatory to the lasting operation so that said lasting operation may be performed more expeditiously, effectively, and economically.

Features of the invention consist in means by which the margin of a counter and upper, whether previously molded or not, may be snugly fitted in outturned relation into the 50 angle between the projecting margin of the

sole and the side of the last about the heel end of the shoe and may be pressed or beaten in said outturned position, and by which the upper may be secured to the last to hold the formed flange and sole in substantially 60 the relation in which they are to be secured together in the subsequent lasting operation. Thus the lasting of the heel portion of the shoe, usually performed by the stitchdown staple lasting machine, may be accomplished 65 much easier and with greater celerity because a less number of lasting and stapling operations is required properly to last and secure the upper.

As herein shown the upper and counter are 70 held against the last by a pair of end embracing members or wipers normally closed yieldingly against the shoe, and means acting, preferably by impact, in a downward and rearward direction effects relative movement between the last and the wipers heightwise of the last to crowd the margin or flange of the upper in outturned relation into the angle between the sole and last. Preferably the flange seating operation, effected 75 by relative movement of the wipers and last, is performed a plurality of times in each cycle, and as herein shown is performed twice yieldingly with varying force, the second operation being more powerful than 80 the first. The tacking mechanism operates automatically to insert a tack through the upper and counter and into the rear end of the last. Preferably the tack is not completely driven so as to facilitate its subsequent removal.

Another feature of the invention consists in flange forming means associated with end embracing wipers and upper securing means. As shown herein the flange former or bender 95 consists of a band-like flange arranged to embrace the last inside of the upper and adjacent to the projecting margin of the sole. By relative movement of the wipers and the flange bender the upper about the end of the shoe is spread outwardly and by relative movement of the wipers and the sole heightwise of the last the upper is made to conform to the end of the last and to the angle between the side of the last and the projecting 100 margin of the sole. The upper is then fastened to the last, for example by a tack driven through the upper and counter and into the end of the last. The flange former 105 may with advantage be given an opening 110

movement to spread the upper at the side of the shoe. Since the resistance of the upper to outward bending is greater at the end than at the sides, this resistance may be utilized to cause the flange former to bend the upper outwardly at the sides prior to its action in bending outwardly the flange at the end.

These and other features of the invention 10 will appear more fully from the following description when read in connection with the accompanying drawings and will be pointed out in the appended claims.

In the drawings,
15 Fig. 1 is a side elevation of a machine embodying the present invention;

Fig. 2 is a plan view, partly in section, of the wipers and their operating mechanism;

20 Figs. 3 and 4 are diagrammatic sectional views illustrating the action of the wipers and pounder in forming a flange on the upper;

Fig. 5 is a side elevation, partly in section, of another embodiment of the invention 25 including flange bending means;

Fig. 6 is a plan view of the construction shown in Fig. 5, the upper being omitted for the sake of clearness;

30 Figs. 7, 8 and 9 are fragmentary views partly in section, illustrating successive positions of the instrumentalities by which the flange is formed on the upper, seated in the angle between the last and sole, and the 35 upper secured to the last.

Referring to Fig. 1 of the drawing, the 40 numeral 2 indicates the frame or column of the machine in the upper portion of which is journaled a cam shaft 4 from which the movements of the various instrumentalities with which the machine is provided are derived. Power rotation of the shaft 4 is controlled by a one-revolution clutch of usual type which is operated by a treadle 45 6 through a treadle rod 8. A work support or jack post 10 telescopes into a jack member 12 pivoted at 14 to the column 2. The post 10 has threaded thereon a sleeve 16 which rests on a jack operating lever 18, 50 pivoted at 20 to the frame. The sleeve 16 has a tongue 22 which engages a slot in the top face of the lever 18 to prevent turning of the sleeve. The height of the post may be adjusted by lifting the post to free the 55 tongue 22 from the slot, turning the sleeve up or down upon the post and reengaging the tongue with the slot. The post is held from turning by a pin 23 engaging a vertical slot in the member 12. The last is held 60 by a pin 24 on the post, and the last support, comprising the post 10 and member 12, is swung about the pivot 14 to carry the last toward and from the machine. When in its outward position as shown by Fig. 1, the 65 post is preferably rigidly supported in order

that the upper may be more readily manipulated relatively to the last to place it in proper position thereon. For this purpose a cam piece 26 is fastened at 28 to the lever 18 so as to fill the space between the lever 18 and a collar 19 which is loose on the rod 10 and rests on the member 12, thus firmly supporting the post. When the support is moved toward the machine the collar 19 moves away from the cam piece 26 and leaves 70 the post 10 supported only by the lever 18. The lever 18 is operated by a rod 29 which has at its upper end operative connections to a cam (not shown) on the shaft 4 by which it is uplifted early in the cycle of operation 75 of the machine in a well-known manner. On the lower end of the rod 29 between the lever 18 and stop nuts 31 on the rod, two springs 30, 32 are arranged, the spring 30 being lighter and longer than the spring 32. 80 When the work support is moved toward the machine it is supported only by the light spring 30 and when, in the power operation of the machine, the rod 29 is raised the spring 30 is compressed and the heavier spring 32 comes into action to sustain the support yieldingly but with considerable force. The spring 32 is held centered on the rod 29 by a flanged washer 34. An adjustable stop 36 is provided on the frame to 85 limit upward movement of the lever 18.

A bracket 40 is fixed to the machine frame by two pins 41, 42 and at its lower end has three legs 43, 44, 45 (Fig. 2) to the lower ends of which a plate 46 is secured by a bolt 47 passing through a slot in the plate and through the leg 44, and by screw bolts 48, 49 which pass through slots in the plate 46 and are threaded into the legs 43, 45 respectively. The front central portion of the plate 46 is 105 cut away sufficiently to receive the end of the largest shoe to be treated. Since the plate 46 is connected to the legs 43, 44, 45 by bolts and slots, by loosening the bolts the plate 46 and parts carried thereby may be adjusted 110 rotarily in the plane of the plate so that a tack which is to be driven in the rear end of the last may be located at one side of the back seam.

Two wiper plates 50, 52 are pivoted at 54 to the plate 46 and are held yieldingly in a normal partly closed position over the opening in the plate by arms 56, 58 pivoted respectively on studs 60, 62 and connected together for equal and opposite movement by toothed segments 64, 66. The outer ends of the arms 56, 58 are urged toward each other by torsion springs 68, 70 suitably connected between the studs 60, 62 and the arms 68 as shown. The outer ends of the arms 56, 58 have pin and slot connections 72, 74 with the wipers 50, 52 and hold them in yieldingly closed position which position is determined and varied by an adjusting stop screw 76. The arms 56, 58 cross each other rearwardly 125 130

of their pivots and the screw 76 is threaded through the end of the arm 58 in position to engage the end of the arm 56 and limit closing of the wipers by the springs 68, 70. 5 Only one of these springs is necessary but two are preferably provided to balance the closing force of the wipers.

Mounted in the bracket 40 is a sliding plunger 80 the lower face 86 of which acts 10 as a pounder or beater. The plunger is arranged for up and down movement at an angle of about 60 degrees to the plane of the wipers 50, 52, and has therefore a substantial component of movement rearwardly. 15 The plunger 80 is slotted at 82 to receive a pin 84 by which its movement is guided. The beating face 86 of the plunger 80 is substantially parallel to the sole of the shoe as presented in the machine and is large 20 enough in area to cover the rear end of the sole including the margin which projects beyond the last bottom. The face 86 is preferably grooved at 87 (Figs. 3 and 4) to avoid contact of the face with the tacks 25 which hold the sole to the last and have to be removed later. To actuate the beater 80 toward the sole a stem 88 is threaded into the upper end of the plunger 80 where it is fixed by a set nut 81. Arranged on the 30 stem 88 are a nut 89, a washer 90, a spring 91, the slotted end of a lever 92 and a clamp collar 93. The lever 92 is pivoted at 94 to the bracket 40 and carries a cam roll 95 which co-operates with a cam 96 having two 35 projections 97, 99, the latter of which extends farther from the center of the shaft 4 than the other. Each rotation of the cam 96 therefore imparts to the plunger 80, through the spring 91, two impulses one of 40 which, preferably the second, is more powerful than the first. It should be borne in mind that the spring 91 is heavier than the spring 32 by which the last is upheld, so that the effect of the blow delivered through 45 the spring 91 will depress the last in the wipers, as will be more fully explained hereinafter.

Between the pivot pin 94 and the lever 92 is an eccentric sleeve 98 by rotation of which 50 the relation of the pivot 94 to the lever may be changed for a purpose to be later explained. The sleeve 98 is rotated by a handle 100 which may be swung between two fixed stops 101, 103, the sleeve being 55 retained yieldingly in either position by a spring plunger 102 engaging suitable notches in a flange on the sleeve 98.

To retract the plunger 80 and maintain 60 the roll 95 in engagement with the cam the spring 91 is utilized. This spring is normally under compression between the washer 90 and the lever 92 and maintains a bearing projection 105 on the collar 93 in engagement with the top side of the lever 92 65 at a point rearwardly offset from the bear-

ing of the spring 91 on the bottom side of the lever. It will be seen that depression of the stem 88, for instance manually, would cause the lever 92 to rock on the projection 105 and its outer end to move away from the 70 collar 93 to further compress the spring 91. The spring 91 tends, therefore, to maintain the lever 92 and the stem 88 in the normal angular relation shown in Fig. 1 to which they return after power displacement. 75

The tacking mechanism by which a tack is driven, as shown in Fig. 4, through the upper and counter and into the rear end face of the last, may be of any usual construction and as shown is similar to that disclosed in 80 United States Letters Patent No. 1,023,794, granted April 23, 1912, on application of Orrell Ashton. A strip of tacks is fed into a slot 110 with the points of the tacks directed outwardly. A feed pawl on a slide 85 112 is operated by suitable connections including a rock-shaft 114 to a rocking member 116 pivoted at 41 to the frame and carrying a roll 118 which engages a suitable cam on the shaft 4 by which the tack strip is advanced the amount of the space between tacks in the strip in each cycle of the machine. The tacks are driven by a driver 120 operated by a lever 122 fulcrumed on a pin 124 about which is coiled a driver spring 95 126. To retract and release the driver a cam roll 128 on the lever 122 is arranged to be engaged by a driver cam 130 which operates the driver in a manner well understood 100 in machines of this class.

In operating the machine above described, the operator threads a loose upper *a* over the post 10 and places on the pin 24 a last *b* having a stitchdown sole or innersole *c* attached to its bottom with its margin projecting beyond the last bottom about its periphery. The operator seizes the upper at each side and lifts it up over the last till the edges of the upper and counter *d* are substantially in the plane of the sole bottom, and adjusts the upper peripherally to position the back seam centrally of the rear end of the last. Then, holding the upper firmly in position, the operator moves the last and positioned shoe parts toward the 105 machine. 110

The rear end of the last enters the yieldingly closed wipers 50, 52 the front corners of which are rounded and beveled to facilitate its entrance as shown in Fig. 2. The wipers hold the upper to the last along a line spaced vertically from the sole as indicated in Fig. 3. While holding the last back in the wipers the operator depresses the treadle 6 to start the machine. The jack lever 18 is raised by upward movement of the rod 29, compressing the spring 30 and causing the last to be sustained by the spring 32. The plunger 80 is then actuated downwardly and rearwardly against the sole on 115 120 125 130

the last, depressing the last against the spring 32 and causing the wipers 50, 52 to wipe the upper toward the sole and crowd or tuck the margin of the upper in out-
5 spread relation into the angle between the side of the last and the projecting margin of the sole. The action of the plunger 80 is preferably repeated with increased force to ensure proper seating of the upper and
10 counter in the angle, and the fastening of the upper may occur either before or after the delivery of the second blow of the member 80. As shown, a tack *e* (Fig. 4) is partially driven automatically through the upper and counter and into the rear end of the last between the blows of the member 80.

In some kinds of work a wedge lift has already been attached to the innersole at the time the upper is assembled. When this is
20 the case an extra thickness of material is presented between the wipers 50, 52 and the beating face 86 of the plunger 80, and it is hence desirable to maintain the amount of compression of the beater spring 91 sub-
25 stantially the same to avoid excessive pressure on the thicker work. This is done by swinging the lever 100 to the left against the stop 101 to raise the fulcrum 94 of the lever 92 as above described and as shown
30 in Fig. 1. For work having no wedge lift on the innersole the lever 100 will be swung against the stop 103.

In the form of mechanism embodying the invention as shown in Figs. 5 to 9, the
35 arrangement is such that the shoe is handled right side up and preferably at a downward and outward inclination. This enables the operator more easily to determine the relative adjustment of the upper and last prior
40 to operation of the machine. A last *b* having an innersole *c* tacked to its bottom and projecting beyond it as usual in this class of work, is placed with its bottom resting on a stationary table 112. Two flange
45 benders 114, 116 are pivoted to a slide 110, at 118, 120, respectively, one on each side of a U-shaped notch in the end of the slide in which the shoe is located. The benders are
50 geared together at 122 for equal and opposite movement about the pivots 118, 120 and their movement is limited in both directions by a pin 124 engaging a suitable elongated notch in the edge of the bender 116. A spring 126 holds the benders normally
55 closed. At their outer portions the benders are shaped to embrace the rear end of a last and along those portions are provided with upstanding flanges 128, 130 the height of which corresponds substantially to the
60 width of the flange to be formed on the upper. The flanges are laterally thin so that the upper may be placed about the last and outside of them in its natural position as shown in Fig. 7. The slide 110 is mounted
65 for movement in guideways 132 formed on

the frame 134 of the machine and has a lug 136 extending down between the guideways 132 in a slot 138 (Fig. 6). The lug 136 is notched to receive a pin 140 on a lever 142 which is pivoted to the frame at 144 and carries between its ends a roll 146 which cooperates with a cam 148 on a cam shaft 150. The lever is moved clockwise to hold the slide 110 in its forward position, as shown in Fig. 5, by a spring 152 suitably arranged about its pivot 144.

The rear end of an unmolded upper *a* is placed about the last outside of the flanges 128, 130 of the flange benders 114, 116, positioned peripherally of the last properly to locate the back seam, and held to the last by the operator who then pushes on the shoe to move the slide 110 rearwardly against the spring 152. This movement carries the roll 146 away from its cam 148, 80 the lever 142 assuming the dotted line position 142' of Fig. 5. When the machine is started, however, the cam 148 picks up the lever 142 and moves it to its second dotted line position 142'', causing action of the 90 flange bender in a manner to be described and retracting the slide 110. The rearward movement of the shoe with the slide brings its rear end between yieldingly closed wiper plates 154, 156 which are pivoted at 158 95 to a cross-head plate 160 attached to the upper ends of rods 162, 164. The wipers 154, 156 are held yieldingly closed by a spring 166 secured to the head 160 and having its ends arranged to press inwardly on 100 studs 168 secured to the wipers 154, 156 respectively and projecting upward through curved slots 170 in the head plate 160. Beneath the table 112 the rods 162, 164 are pivoted to one end of a link 172 the other 105 end of which is pivoted at 174 to the frame 134. The lower portions of the rods are reduced and pass through a bar 176 journaled in a lever 178 between its ends. One end of the lever is pivoted at 180 to the frame and at the other carries a roll 182 which cooperates with a cam 184 on the 110 shaft 150. Between the bar 176 and the lower ends of the rods 162, 164 strong compression springs 186 are arranged. A tension spring 188 is arranged between the lever 178 and the frame 134 to hold the roll 182 against its cam and to raise the 115 plate 160 and the wipers carried by it. Since the direction of downward movement of the wipers 154, 156 is at a substantial angle to the plane of the sole of the shoe presented on the table 112, the wipers, when depressed, have a component of movement forward lengthwise of the shoe to crowd 120 the outwardly turned margin of the upper closely into the angle between the side of the last and the projecting margin of the sole at the rear end of the shoe. The cam 184 has preferably two projections 125 185, 187 130

which act to impart two successive depressions to the wipers in each cycle of the machine. The projection 187 is higher than the projection 185 so that upon the second depression of the wipers the springs 186 will be more strongly compressed and greater pressure applied by the wipers to the shoe flange.

On the plate 160 is a bracket 190 to which 10 a tacker head 192 is secured by a pivot clamping bolt 194. Tacks are supplied in any usual manner to the tacker head 192 through a tack tube 196 to be driven by a driver 198 on a driver bar 200 connected by 15 a link 202 to one arm of an angle driver lever 204. The lever is pivoted to the frame at 206 and has on its other arm a roll 208 engaging a driver cam 210. The lever is actuated by the usual driver spring 212 20 suitably arranged about its pivot 206.

The operator, having positioned the upper on its last and pushed the slide rearwardly to bring the rear end of the shoe within the yielding embrace of the wipers 25 154, 156, starts the machine by depressing a treadle in the usual manner. As the shaft 150 rotates the cam 148 picks up the roll 146 which is then in position 146' and moves the lever 142 to retract the slide 110 and 30 cause the bender flanges 128, 130 to begin to bend the rear portion of the margin of the upper and counter outwardly (Fig. 7). The formation of the cam 148 at 148' causes the benders to move slowly at first in effecting 35 the initial bending of the flange. The resistance to outward bending of the margin is, however, usually greater at the rear end than at the sides. In that case the benders will turn on their pivots 118, 120, causing 40 the upper margin at the sides to be bent outwardly first. When the opening movement of the benders has been arrested by the pin 124 the benders move bodily rearwardly and bend outwardly the rear portions of the 45 flange (Fig. 8) and when the rearward movement of the bender slide 110 has proceeded far enough to remove the bender from beneath the wipers and head plate 160, these begin to descend because of the action 50 of the cam 184 on the lever 178 which, through the springs 186 and rods 162, 164, effects downward movement of the wipers 154, 156. The wipers, because of their component of forward movement relatively to 55 the last in addition to their downward movement, carry the inturned flange of the upper forwardly of the last as well as downwardly and tuck the angle of the flange snugly into the angle between the side of the last and the projection of the sole, as shown in Fig. 9, this angle being somewhat acute in most lasts as shown. After the first depression of the wipers by the cam projection 185 they are slightly released and immediately depressed again more forcibly by

the projection 187 to complete the formation and positioning of the upper in the angle. The cam 210 then operates to release the driver and a tack *e* is partially driven through the upper and counter and into the 70 rear end of the last (Fig. 9). The tacker nozzle may be shifted laterally by loosening the bolt 194 so that the tack will be driven at one side or the other of the back seam to avoid cutting of the back seam stitches. 75 The machine, having completed its cycle, stops with the shoe released. In the drawing (Figs. 5 to 9) the innersole is shown as having a wedge or beveled lift *f* attached thereto. The machine will operate on shoes having no wedge lift but in order to secure full effectiveness of the flange benders and full pressure of the wipers it may be desirable to provide, between the sole and the 80 table, a thickness of material substantially 85 equal to that of a wedge lift, for example a metal plate.

The shoe, having been assembled as described, is ready for the operations of staple lasting, and since the upper has been already flanged and worked into the angle in which it is to lie when lasted the labor of staple lasting is greatly reduced, it being necessary only to insert a few staples to re-establish the upper in the angle and secure 90 it to the projection of the sole about the heel-seat.

Having thus described my invention, what I claim as new and desire to secure by Letters Patent of the United States is: 100

1. In a machine for assembling an upper upon a last having a sole attached thereto, the combination of means for pressing an upper and counter against the side faces of the last, means for effecting relative movement between the last and the pressing means to work the upper toward the sole, and means for securing the upper to the last. 105

2. In a machine for assembling an upper upon a last having a sole attached thereto, the combination of means for pressing an upper and counter against the side faces of the last, means for effecting relative movement between the last and the pressing means to work the upper toward the sole, and means for fastening the upper to the last. 110

3. In a machine for assembling an upper upon a last having a sole attached thereto, the combination of means for pressing an upper and counter against the end and side faces of the last, means for effecting relative movement between the last and the pressing means to work the upper toward the sole, and means for fastening the upper to the end of the last. 115

4. In a machine for assembling an upper upon a last having a sole attached thereto, the combination of means for pressing an upper and counter against the side faces of 120

the last, means for effecting relative movement between the last and the pressing means to work the upper toward the sole, and means for inserting a fastening through 5 the upper and counter and into the end face of the last.

5. In a machine for assembling an upper upon a last having a sole attached thereto and projecting beyond the edge of the last 10 bottom, the combination of end embracing means into which the shoe is presented to crowd the upper against the last adjacent to the angle between the side of the last and the projecting margin of the sole, means 15 for engaging the sole, and means for effecting relative movement between the embracing means and the sole engaging means including movement heightwise of the shoe 20 to cause the upper to be seated in outturned relation in said angle.

6. In a machine for assembling an upper upon a last having a sole attached thereto and projecting beyond the edge of the last bottom, the combination of end embracing 25 means into which the shoe is presented to crowd the upper against the last adjacent to the angle between the side of the last and the projecting margin of the sole, means for engaging the sole, and means for 30 effecting relative movement heightwise of the last between the embracing means and the sole engaging means to cause the upper to be seated in outturned relation in said angle.

35 7. In a machine of the class described, means for forming an outturned flange upon an upper placed about a last, and means for securing the upper to the last.

40 8. In a machine of the class described, the combination of means for tucking an upper in outturned relation into the angle between the side of a last and the margin of a sole attached to the last, and means for fastening the upper to the last.

45 9. In a machine of the class described, the combination of means for tucking an upper in outturned relation into the angle between the side of a last and the margin of a sole attached to and extending beyond 50 the bottom of the last, and means for securing the upper to the last.

55 10. In a machine of the class described, the combination of means for tucking an upper in outturned relation into the angle between the side of a last and the margin of a sole attached to the last, and means for securing the upper to the last at a point spaced heightwise of the last with respect to the sole.

60 11. In a machine of the class described, the combination of means for tucking an upper in outturned relation into the angle between the side of a last and the margin of a sole attached to the last, and tacking 65 means acting automatically to secure the

upper to the last to hold the upper in assembled relation on the last.

12. In a machine of the class described, the combination of means for conforming 70 an upper and counter about the rear end of a shoe into the angle between the side of the last and the margin of a sole attached to the last and extending beyond the last bottom, and means for inserting a tack through the upper and counter and into the 75 end of the last.

13. In a machine of the class described, the combination of means for conforming 80 an upper and counter to the angle between the side of the last and the margin of a sole attached to the last, and means for inserting a tack through the upper and counter and into the end of the last.

14. In a machine of the class described, the combination of continuous means for 85 conforming an upper and counter to the angle between the side of the last and the margin of a sole attached to the last about the periphery of the end of a shoe, and means for beating the tread face of the sole 90 over the conformed upper and counter to force the sole and the conformed counter together.

15. In a machine for assembling the uppers of stitch-down shoes upon their lasts 95 preparatory to lasting, the combination of last end embracing means acting yieldingly to force the upper against the last about its rear end with the upper outturned, and means for effecting relative movement between the embracing means and the last to wipe the upper heightwise and form an angle in the upper.

16. In a machine for assembling the uppers of stitch-down shoes upon their lasts 105 preparatory to lasting, the combination of last end embracing means acting yieldingly to force the upper against the last about its rear end with the upper outturned, sole engaging means, and means for effecting relative movement between the end embracing 110 means and the sole engaging means to seat the outturned flange against the sole.

17. In a machine for assembling the uppers of stitch-down shoes upon their lasts 115 preparatory to lasting, the combination of last end embracing means acting yieldingly to force the upper against the last about its rear end with the upper outturned, sole engaging means, and means for effecting relative movement between the end embracing means and the sole engaging means to cause the embracing means to wipe the upper toward the sole and to seat the outturned flange against the margin of the sole.

18. In a machine for assembling the uppers of stitch-down shoes upon their lasts 120 preparatory to lasting, the combination of last end embracing means acting yieldingly to force the upper against the last about its 125 margin of the sole.

5 rear end with the upper outturned, sole engaging means, means for effecting relative movement between the end embracing means and the sole engaging means to seat the outturned flange against the sole, and means for securing the upper to the end of the last while the upper is held in seated position.

10 19. In a machine for assembling an upper upon a last having a sole attached thereto, the combination of means comprising a pair of normally partially open and yieldingly closed wipers between which the end of a shoe may be thrust for pressing the upper 15 and counter against the end and side faces of the last, means for effecting relative movement between the last and the wipers to work the upper toward the sole, and means for securing the upper to the end of 20 the last.

20 20. In a machine for assembling stitch-down shoe uppers upon their lasts preparatory to lasting, the combination of means for shaping the upper to the last about the 25 periphery of the rear portion thereof, and means for delivering successive blows to the heel seat portion of the sole.

30 21. In a machine for assembling stitch-down shoe uppers upon their lasts preparatory to lasting, the combination of means for shaping the upper to the last about the rear portion thereof, and means for delivering successive blows of increasing intensity to the sole.

35 22. In a machine for assembling stitch-down shoe uppers upon their lasts preparatory to lasting, the combination of means for shaping the upper to the last about the rear portion thereof, means for beating the sole, and means for securing the upper to the last.

40 23. In a machine of the class described, the combination of means for conforming an upper and counter to the angle between the side of the last and the margin of a sole attached to the last, means for beating the sole against the conformed upper, and means acting after the beating means to insert a fastening to hold the upper to the last.

45 24. In a machine for assembling stitch-down shoe uppers upon their lasts preparatory to lasting, the combination of means for conforming the upper to the last about the rear portion thereof to the angle between the last and a sole projecting beyond the last bottom, and means for beating the sole.

50 25. In a machine for assembling the upper of a stitch-down shoe upon its last, said last having a sole previously attached thereto with its margin projecting beyond the side of the last, the combination of a last support movable toward and from the machine, yieldingly closed wipers between 55 which the shoe is moved on the support to

force the upper against the side face of the last about its rear portion, and means for effecting relative movement between the wipers and last heightwise of the last to cause the wipers to seat the upper in outturned relation in the angle between the side of the last and the projecting margin of the sole.

70 26. In a machine for assembling an upper upon a last having a sole attached thereto, the combination of means for pressing the upper and counter against the side faces of the last, means comprising a yieldingly actuated beater engaging the margin of the sole about the periphery of the heel-seat for effecting relative movement between the last and the pressing means to work the upper toward the sole, and means for fastening the upper to the last.

75 27. In a machine for assembling an upper upon a last having a sole attached thereto and projecting beyond the edge of the last bottom, the combination of end embracing means into which the shoe is presented to crowd the upper against the last adjacent to the angle between the side of the last and the projecting margin of the sole, and means for engaging the sole and effecting movement of the last and sole relatively to the embracing means to cause said means 90 to force the upper in outturned position into said angle.

80 28. In a machine for assembling an upper upon a last with a sole attached thereto and projecting beyond the edge of the last bottom, the combination of end embracing means into which the shoe is presented to crowd the upper against the last adjacent to the angle between the side of the last and the projecting margin of the sole, and means 95 for delivering a blow to the sole bottom to cause the last to be depressed relatively to the wipers to cause the wipers to seat the upper in the said angle.

85 29. In a machine for assembling an upper upon a last with a sole attached thereto and projecting beyond the edge of the last bottom, the combination of end embracing means into which the shoe is presented to crowd the upper against the last adjacent to 100 the angle between the side of the last and the projecting margin of the sole, and means for delivering a plurality of blows to the sole bottom to cause the last to be depressed relatively to the wipers to cause the wipers 105 to seat the upper in the said angle.

110 30. In a machine for assembling an upper upon a last with a sole attached thereto and projecting beyond the edge of the last bottom, the combination of end embracing means into which the shoe is presented to crowd the upper against the last adjacent to the angle between the side of the last and the projecting margin of the sole, and means 115 for delivering a plurality of blows to the 120 sole bottom to cause the last to be depressed relatively to the wipers to cause the wipers to seat the upper in the said angle.

125 31. In a machine for assembling an upper upon a last with a sole attached thereto and projecting beyond the edge of the last bottom, the combination of end embracing means into which the shoe is presented to crowd the upper against the last adjacent to the angle between the side of the last and the projecting margin of the sole, and means 130 for delivering a plurality of blows to the

creasing intensity to the sole bottom to cause the last to be depressed relatively to the wipers to cause the wipers to seat the upper in the said angle.

5 31. In a machine for assembling uppers upon their lasts preparatory to lasting, a support to receive the last, means for holding the rear portion of an upper placed about the last against the ends and sides of the last, means for forming the margin of the upper into an outturned flange and pressing said flange flat in a plane parallel to the last bottom, and means for fastening the upper to the end face of the last.

10 32. In a machine for assembling an upper upon a last having a projecting sole attached thereto, the combination of means comprising a pair of normally partially open and yieldingly closed wipers between which the end of a shoe is thrust to press the upper and counter against the end and side faces of the last and against the edge face of the sole, power operated means including a cam for causing relative movement between the last and the wipers to effect heightwise and forward movement of the upper toward the sole, and means for securing the upper to the end of the last.

15 33. In a machine for assembling an upper upon a last having a projecting sole attached thereto, the combination of wipers for pressing the upper and counter against the side faces of the last and the edge face of the sole, a yieldingly actuated beater engaging the margin of the sole about the periphery of the heel-seat for depressing the last relatively to the wipers to press the upper against the sole, and means for inserting a fastening through the upper substantially perpendicularly to the end face of the last.

20 34. In a machine for assembling an upper upon a last with a sole attached thereto and projecting beyond the edge of the last bottom, the combination of end embracing means into which the shoe is presented, a last support movable toward and from the embracing means, a light spring for sustaining the support when the shoe is presented, power means including a strong spring for depressing the last to cause the embracing means to wipe the upper toward the last bottom and a spring of intermediate strength tending to sustain the last during said depression.

25 35. In a machine for forming an upper on a last, means for forming a sole attaching flange, and end embracing wipers operating heightwise of the last to wipe the upper toward the last bottom.

30 36. In a machine for forming uppers, a support for the bottom of a sole attached to a last, a member embracing the end of the last and engaging the inside of an upper placed over the last, means to hold the upper

against the last, and means for relatively moving the last and the embracing member to flange the upper.

37. In a machine for forming uppers, a support for the bottom of a sole attached to a last, a spreader embracing the end of the last above the sole, means for conforming the upper to the last above the spreader, and means for relatively moving the spreader and the conforming means to spread the margin of the upper to form a flange.

70 38. In a machine for forming uppers, a support for the bottom of a sole attached to a last, a spreader embracing the end of the last above the sole, means for conforming the upper to the last above the spreader, means for relatively moving the spreader and the conforming means to spread the margin of the upper to form a flange, and means for securing the upper to the last.

75 39. In a machine for forming uppers, a support for the bottom of a sole attached to a last, a spreader embracing the end of the last above the sole, means for conforming the upper to the last above the spreader, means for relatively moving the spreader and the conforming means to spread the margin of the upper to form a flange, and means to move relatively the support and the conforming means to force the flange against the sole.

80 40. In a machine for forming uppers, a support for the bottom of a sole attached to a last, a spreader embracing the end of the last above the sole, means for conforming the upper to the last above the spreader, means for relatively moving the spreader and the conforming means to spread the margin of the upper to form a flange, means to move relatively the support and the conforming means to force the flange against the sole, and means for securing the upper to the end of the last.

85 41. In a machine of the class described, a support for a sole projecting beyond the bottom of its attached last, a flanging member extending heightwise of the last substantially as much as the width of the flange to be formed, said member being thin laterally so as to permit placing of an upper over the flanging member in substantially its natural position on the last with its edge substantially in the plane of the sole, means to hold the upper against movement rearwardly of the last, and means for moving the member rearwardly relatively to the holding means.

90 42. In a machine of the class described, a support for a sole projecting beyond the bottom of its attached last, a flanging member extending heightwise of the last substantially as much as the width of the flange to be formed, said member being thin laterally so as to permit placing of an upper over the flanging member in substantially

- its natural position on the last with its edge substantially in the plane of the sole, means above the member to hold the upper against movement rearwardly of the last, means for 5 moving the flanging member rearwardly relatively to the holding means, and means for moving the holding member toward the sole to lay the formed flange against the projection of the sole.
- 10 43. In a machine for assembling an upper upon a last having a sole attached thereto and projecting beyond the edge of the last bottom, the combination of end embracing means into which the shoe is presented to 15 crowd the upper against the last adjacent to the angle between the side of the last and the projecting margin of the sole, means for turning the margin of the upper outwardly and means for effecting relative 20 movement between the last and sole and the embracing means to force the upper in out-turned position into said angle.
44. In a machine of the class described, the combination of means for forming an 25 outturned flange on an upper, means for tucking the outturned upper into the angle between the side of the last and the margin of a sole attached to the last, and means for fastening the upper to the end of the last.
- 30 45. In a machine for assembling uppers upon their lasts preparatory to lasting, a support to receive the last right side up, means for holding the rear portion of an upper placed about the last against the ends 35 and sides of the last, means for forming the margin of the upper into an outturned flange, and means for fastening the upper to the last.
46. In a machine for assembling uppers 40 upon their lasts preparatory to lasting, a support to receive a last right side up in a downwardly and outwardly inclined position toward the operator, means for working downwardly and forwardly an upper 45 placed about the last, and means for fastening the upper to the last.
47. In a machine for assembling uppers 50 upon their lasts preparatory to lasting, a support to receive a last right side up in a downwardly and outwardly inclined position toward the operator, means for forming an outturned flange upon the upper, means engaging the upper at the angle of the flange with the upper, means for effecting relative movement between the angle 55 engaging means and the last to work the upper downwardly and forwardly relatively to the last, and means for fastening the upper to the last.
- 60 48. In a machine for assembling uppers upon their lasts preparatory to lasting, a support to receive a last right side up in a downwardly and outwardly inclined position toward the operator, means for forming an outturned flange upon the upper, 65 means embracing the shoe adjacent to the line where the upper is outturned to form the flange, and means for operating the embracing means heightwise of the last to seat the angle of the flange in the angle between the side of the last and the projecting margin of the sole.
- 70 49. In a machine of the class described, the combination of means for forming an outturned flange on an upper, means for tucking the outturned upper into the angle between the side of the last and the margin of the sole attached to the last and repeatedly pressing the outturned portion against the sole, and means for inserting a fastening to hold the upper to the end face of the last.
- 75 50. In a machine for assembling uppers upon their lasts preparatory to lasting, a support to receive a last right side up in a downwardly and outwardly inclined position toward the operator, wipers embracing an end of the last and power operated means for effecting a plurality of movements of the wipers heightwise of the last with a component of forward movement to work downwardly and forwardly an upper placed about the last, and means for fastening the upper to the last.
- 80 51. In a machine for assembling uppers upon their lasts preparatory to lasting, a support to receive a last having a projecting sole attached thereto right side up and in a downwardly and outwardly inclined position toward the operator, means for forming an outturned flange upon the upper, wipers engaging the upper at the angle of the flange with the upper, means including a cam and lever connections for effecting substantially vertical movement of the wipers to work the upper downwardly and forwardly relatively to the last and against the projecting sole, and means for fastening the upper to the last.
- 85 52. In a machine for assembling uppers upon their lasts preparatory to lasting, a support to receive a last right side up in a downwardly and outwardly inclined position toward the operator, flange benders for forming an outturned flange upon the upper, a pair of wipers embracing the shoe adjacent to the line where the upper is outturned to form the flange, and power operated, cam controlled means for moving the wipers heightwise of the last to seat the angle of the flange in the angle between the side of the last and the projecting margin of the sole.
- 90 53. In a machine of the class described, the combination with upper securing means, of flange forming means comprising wipers to hold the upper against the end and sides of the last, and a flange bender engaging inside the upper and movable outwardly of the last to form a flange against the wipers.
- 95 100 105 110 115 120 125 130

54. In a machine of the class described, the combination with upper securing means, of flange forming means comprising wipers arranged to hold the upper against the end 5 and sides of the last, a flange bender engaging inside the upper and movable outwardly of the last to form a flange against the wipers, and means for actuating the wipers to press the outturned upper against the 10 projection of the sole upon the last.

55. In a machine of the class described, the combination with upper securing means, of flange forming means comprising wipers arranged to hold the upper against the end 15 and sides of the last, a flange bender engaging inside the upper and movable outwardly of the last to form a flange against the wipers, and means for actuating the

wipers a plurality of times in each cycle to press the outturned upper against the projection of the sole upon the last. 20

56. In a machine of the class described, the combination with upper securing means, of flange forming means comprising wipers arranged to hold the upper against the end 25 and sides of the last, a flange bender engaging inside the upper and movable outwardly of the last to form a flange against the wipers, and means for actuating the wipers a plurality of times in each cycle 30 with increasing pressure to press the outturned upper against the projection of the sole upon the last.

In testimony whereof I have signed my name to this specification.

NORWOOD H. KNOWLTON.
